UNITED STATES PATENT OFFICE

ELIAS SPECTER, OF BROOKLYN, NEW YORK, ASSIGNOR OF ONE-HALF TO BILT-RITE
BABY CARRIAGE CO., OF BROOKLYN, NEW YORK, A FIRM COMPOSED OF MYER S.
HARRISON AND ELIAS SPECTER, AND ONE-HALF TO COLLIER-KEYWORTH CO., OF
GARDNER, MASSACHUSETTS, A CORPORATION OF MASSACHUSETTS

LOCK FOR BABY-CARRIAGE BACKS

Application filed June 1, 1927. Serial No. 195,839.

This invention relates to an improvement in a lock for a baby carriage back and the novelty resides in the adaptation and arrangement of parts as will be more fully hereinafter pointed out.

There are several types of locks in use for the backs of baby carriages, most of which lock the back in the closed or open position but do so in a manner which does not insure any rigidity.

My device is adapted to lock the back of a baby carriage only in the closed position but does so in a way which absolutely insures the rigidity of said back in the locked position while permitting the back to vary in position when tilted back in the unlocked position.

It combines an effectiveness in locking in the closed position which has heretofore not been attained and is also of a simple and inexpensive construction peculiarly adapted to the problem to be solved.

Referring to the drawings Figure 1 is a vertical sectional view of a portion of a baby carriage frame and back hinged thereto showing my complete device in locked position, portions being broken away for convenience in illustration.

Figure 2 is the same as Figure 1 but showing my device in the unlocked position.

Figure 3 is a bottom plan view of the edge of the back, a portion being broken away for convenience in illustration.

Figure 4 is a perspective of the locking plate and Figure 5 is a perspective of the reinforcing plate.

In the drawings 6 is a locking plate adapted to be secured at 7 in the usual well known manner to a baby carriage frame 8 and it has a slot 9 with two downturned guide plate members 10 bordering one end of the slot 9 and the opposite end of the slot 9 terminating in a downturned lip 11 constituting a part of the plate 6. A reenforcing plate 12 is rigidly secured in the usual well known manner at 13 to the base of a baby carriage back 14 so that the lower end of said plate 12 extends slightly below the lower end of the back 14 and said back 14 is hinged at 15 to the frame 8 in the usual well known manner. The frame 50 8 has a cut out portion 16 adapted to receive

the projecting portions of the locking mechanism.

A locking bar 17 is mounted through the back 14 so that it will slide readily therethrough and in a cut out portion 18 of said back 14 a spiral spring 19 is mounted over said locking bar 17 between a washer 20 which bears on the lower end of the cut out portion 18 of the back 14 and a washer 21 held in position over the upper end of the spring 19 by means of cotter pin 22 which passes through said locking bar 17. The lower end of the locking bar 17 terminates in a flattened portion 23 adapted to pass through the slot 9 of the locking plate 6 and a cylindrical pin 24 is rigidly secured through said flattened portion 23 and is adapted to hold the lower end of said locking bar 17 in the engaged position in said slot 9. On the upper end of the locking bar 17 is threaded in the usual well known manner a suitable handle 25.

In operating my device the locking bar which is under normal upward pressure due to the spring 19 pressing against the washer 21 causes a continuous normal pressure of the pin 24 on the underside of the two downturned guide plates 10 in the unlocked position as indicated in Figure 2. As the back 14 is restored to the closed position by pushing the same on the outer side thereby closing hinges 15 the pin 24 will ride down on the downturned guide plates 10 until being under the spring pressure 19 the bar 17 is pulled by said spring 19 upwardly as the pin 24 passes off of the inside ends of the guide plates 10 whereby said pin 24 goes to the full locked position between the ends of the guide plates 10 and the downturned lip 11 thereby holding the locking bar 17 rigidly in a locked position and simultaneously the lower end of the reinforcing plate 12 will contact with the locking plate 6 thereby effecting a rigidity between the back 14 and the frame 8 which could not otherwise be obtained, as shown in Figure 1.

When it is desired to unlock the back 14 the operator merely presses down on the handle 25 thereby compressing spring 19 and throwing the pin 24 out of engagement between the ends of the guide plates 10 and 100

the downturned lip 11 so that the back 14 may be pulled backward on the hinges 15 and the flattened portion 23 of the locking bar 17 will pass through the slot 9 and as the operator releases the pressure on the handle 25 the pin 24 will contact with the underside of the downturned guide plates 10 whereby the back 14 will be opened to the position as shown in Figure 2.

It is apparent that the back 14 may have considerable play as to its position when unlocked due to the varying position which may be taken by the pin 24 on the underside of the downturned guide plates 10 and such variation in the position of the back 14 is most desirable in the use of a baby carriage and in fact this results in the back 14 assuming the particular position which may best accommodate the child in the baby carriage as said child presses against the back 14 when it is in its unlocked position.

It will be apparent that many variations may be made in the actual structure of my device without departing from the spirit and intent of the same.

I claim:

1. In a baby carriage back lock the combination of a back, a locking bar mounted through said back under constant upward spring tension, a cross frame, a locking plate mounted rigidly in said cross frame having a slot with two downturned guide plates bordering one end of said slot, a downturned lip terminating the opposite end of said slot, the lower end of said locking bar passing through said slot and a cross pin securing it in said slot, and a reenforcing plate rigidly secured to the inside lower edge of the back so as to project slightly therefrom and bind against the locking plate.

2. In a baby carriage back lock the combination of a back, a locking bar mounted through said back under constant upward spring tension, a cross frame, a locking plate mounted rigidly in said cross frame having a slot with two downturned guide plates bordering one end of said slot, a downturned lip terminating the opposite end of said slot, the lower end of said locking bar moving in said slot and limited by a cross pin engaging in locked position between said downturned guide plates and lip and said cross pin rolling on said guide plates in the unlocked position, and a reenforcing plate rigidly secured to the inside lower edge of the back so as to project slightly therefrom and bind against the locking plate.

3. In a lock for a hinged member the combination of a hinged member, a locking bar mounted through said hinged member under constant upward spring tension, a cross frame in a fixed member, a locking plate mounted rigidly in said cross frame on which the hinged member is mounted, a slot in said plate with two downturned guide plates

bordering one end of said slot, a downturned lip terminating the opposite end of said slot, the lower end of said locking bar passing through said slot and a cross pin securing it against removal from said slot, and a re-enforcing plate rigidly secured to the inside lower edge of the hinged member so as to project slightly therefrom and bind against the locking plate.

4. In a lock for a hinged member the combination of a hinged member, a locking bar mounted through said hinged member under constant upward spring tension, a cross frame in a fixed member, a locking plate mounted rigidly in said cross frame on which the hinged member is mounted, a slot in said plate with two downturned guide plates bordering one end of said slot, a downturned lip terminating the opposite end of said slot, the lower end of said locking bar passing through said slot and a cross pin securing it against removal from said slot, the lower end of said locking bar moving in said slot and limited by said cross pin engaging in locked position between said downturned guide plates and lip and said cross pin rolling on said guide plates in the unlocked position, and a reenforcing plate rigidly secured to the inside lower edge of the hinged member so as to project slightly therefrom and bind against the locking plate.

5. In a baby carriage having a hinged back, a locking bar under constant downward pressure mounted therein and passing through a locking plate at its lower end and having a cross pin near said lower end, said locking plate comprising a central slot with two downturned guide plates bordering one end of said slot and a downturned lip terminating the opposite end of said slot.

5. In a baby carriage having a hinged back, a locking bar under constant downward pressure mounted therein and passing through a locking plate at its lower end and having a cross pin near said lower end, said locking plate composed of a central slot with two downturned guide plates bordering said slot and a downturned lip at one end of the slot adjacent the open downturned ends of said guide plates.

In testimony whereof I affix my signature.

ELIAS SPECTER.
